DUPLICATING MACHINE

Frank Ronald Ford, Sparkbrook, Birmingham,
EnglandApplication December 11, 1941, Serial No. 422,501
In Great Britain July 23, 1941

10 Claims. (Cl. 101—132.5)

This invention relates to improvements in or modifications of the invention forming the subject of prior specification U. S. A. application No. 372,119 wherein I have described a duplicating machine in which provision is made for moistening the copy sheets sectionally so that when a master sheet is secured to the cylinder with the lines of writing thereon extending circumferentially the matter reproduced on the copy sheet may be confined to any one or more of such lines.

In specification U. S. A. application 372,119 the machine comprises a carriage mounted on guides for movement parallel to the axis of the cylinder the carriage having thereon a plurality of pressure rollers of line or paragraph width and a corresponding number of moistening members of approximately corresponding width, said moistening members being mounted for movement manually in and out of the operative position, and a pressing member for pressing the copy sheets against the moistening member or members which is in the operative position, said pressing member being automatically raised from its operative position once each revolution of the cylinder to allow of the insertion of a copy sheet.

The object of the present invention is to provide certain improvements in or modifications of the machine disclosed in the prior specification.

One of the modifications in accordance with the present invention consists in the provision of a coupling operating between each pressure roller and its associated moistening member whereby the operation of a single operating member moves both into or out of the operative position simultaneously.

Each pressure roller may be adapted to be moved by a cam into its operative position and this cam can be operated to permit the pressure roller to move into the inoperative position and motion transmitting means such as a Bowden cable being connected to the cam and to the associated moistening member whereby the roller and the pad are moved in sympathy.

A push pin may be interposed between the cam and the stem carrying the pressure roller there being a spring operating between the head of the said pin and the end of the stem.

Further according to the present invention the operating gear for two pressure rollers may be mechanically or otherwise coupled together so that when one is moved into the operative position the other is moved into the inoperative position.

The movement of each moistening member into

its operative position may be assisted by a spring and a stop may be provided to limit the movement of each moistening member away from its operative position.

This stop may be in the form of a head and pivoted plate which is capable of being moved into an inoperative position to allow of the complete removal of the moistening pads.

The moistening pads or members may be mounted to slide on the top of the tank between adjustable guide plates so that the positions of the said members or pads can be adjusted laterally.

The casing of each moistening member may be constructed so that when the pad is moved into its inoperative position contact between the pad and the associated wick is severed by a part of the casing.

In the prior specification I have disclosed a depression at the periphery of the cylinder which enables the copy sheets to be inserted between the pressure rollers and the cylinder without difficulty and according to a further part of the present invention this depression which is adjacent the master sheet clip is made to act as a cam to produce endwise movements of the pressure roller stems. Further these stems may be provided with lugs operating upon levers carrying the pressing member for the moistening members.

According to a further modification in accordance with this invention the carriage may be of articulated construction whereby the portion which carries the pressure rollers and associated parts is enabled to make a pivotal movement about a horizontal axis to give ready access to the working parts mounted thereon and to the upper part of the cylinder.

Referring to the drawings:

40 Figure 1 is a plan view showing a machine constructed in accordance with this invention.

Figure 2 is a section on line 2—2 of Figure 1.

Figure 3 is a section on line 3—3 of Figure 2.

Figure 4 is a plan view showing the top of the tank and associated parts.

Figure 5 is a sectional view showing the stop plate used for the moistening members.

Figure 6 is a perspective view of one of the moistening members and its casing.

50 Figure 7 is a back view of the two pressure rollers and associated mechanism.

In the construction illustrated the general design of the machine does not differ from that shown in the prior patent. The cylinder is shown at 10 and is mounted for rotation with a shaft

11 the shaft being mounted in the side plates 12 of the frame of the machine. The side plates 12 are held in spaced relationship in the usual way by means of tie bolts, two of which are indicated at 13.

The cylinder 10 is provided with a clip 14 for holding the master sheet 15 and adjacent the clip 14 the periphery of the cylinder is formed with a depression 16.

Two brackets 17 are mounted upon the upper edges of the side members 12 of the machine frame and these brackets carry a guide rod 18.

The machine is provided with a laterally moving carriage which comprises a tank 19 for containing moistening fluid and a box 20 carrying the stems of the pressure rollers which press the copy sheets on to the master sheet. The box 20 is guided on the rod 18 the box being provided with ball bearing rollers 21 mounted in brackets 22.

A similar provision is made in the tank 19 which is provided with a tube 23 and with ball bearing rollers 24 engaging one of the bolts 13.

The carriage can thus move laterally with a minimum of friction and the means for moving the carriage in this way is that described in the prior specification.

The tank 19 has associated with it a glass vessel 104 connected by a metal tube 105 to the tank so that the level of the liquid in the tank will show in the vessel 104.

The tank 19 is formed with two end plates one of which can be seen at 25 and these end plates are extended upwardly to form bracket like structures 26 which carry between them a pair of bars 27 upon which rests the feed tray 28.

Secured to the ends of the bars 27 are further brackets 29. These brackets carry a rod 30 extending parallel to the axis of the cylinder and mounted on this rod are brackets 31 carrying the box 20.

Normally the brackets 31 are fixed to the rod 30 by grub screws 32 but these grub screws can be removed and the arms 31 together with the box and all parts mounted therein and thereon can be rotated about the axis of the rod 30 in a clockwise direction (Figure 2) in order that easy access may be obtained to the parts protruding from the under side of the box. This action also permits of access to the upper part of the cylinder when required.

Extending between the end portions of the arms 31 are two rods 33 and secured to these rods by screws 34 is a cheek plate 35 forming one side of the box. The opposite side of the box is shown at 36 and the top of the box is shown at 37. Mounted for vertical sliding movement in the box are the stem 38 carrying the pressure rollers 39. These pressure rollers may be both of line width or both of paragraph width but preferably one is of paragraph width and the other is of line width.

The lower ends of the stems 38 are forked and provided with pins 40 upon which the rollers 39 are mounted.

At its upper end each stem is bored as shown at 41 and provided with a push pin 42 having a head 43. A coil spring 44 is mounted on the push pin and operates between the top of the stem and the underside of the head 43.

Mounted horizontally in the upper part of the box is a cam shaft 45 for each stem 38 upon which shaft is a cam 46 operable by a lever 47.

These levers 47 may be releasably coupled together by a link 100 having a wide centre part

101 into which the screws 102 carried by the levers can be moved when it is desired to release the coupling. Each lever may have a finger piece 103 secured to it by the screw 102. This coupling enables the rollers to be operated so that when one is moved into the operative position the other is automatically moved into the inoperative position.

The cam shaft 45 extends through the plate 36 and at the exterior thereof is provided with a cap 98 carrying a spring pressed ball 99 engaging with either of two spaced recesses in the plate 36 and thus serving to retain the cam in either of its two terminal positions. The cap 98 carries adjustably an indicator arm 48 which cooperates with an indicator sheet similar to the master and mounted upon a support 49. When the cam 46 is in the position it occupies when the corresponding pressure roller 39 is in operation the indicator arm 48 is raised. If however the cam is operated so as to take the pressure roller 39 out of operation the indicator arm 48 is lowered.

As shown in Figure 3 the cam is in the position it occupies when the pressure roller 39 is in operation. In order to take the pressure roller out of operation the lever 47 (see Figure 3) is moved in a clockwise direction.

Projecting from the side of each of the stems 38 is a lug 50 and on its upper side each of these lugs is provided with an eye 51 connected by a tension spring 52 to a pin 53 attached to the plate 36. Thus when the cam is operated to allow the stem 38 to rise the stem is pulled upwardly by the spring 52 thus taking the pressure roller 39 out of operation.

During normal working when the cam is in the position shown in Figure 3 the pressure roller 39 projects somewhat into the space formed by the depression in the surface of the cylinder when the cylinder is driven however it raises the pressure roller 39 slightly thus compressing the spring 44 whereby the roller 39 bears with light pressure on the top of the copy sheet and presses it on to the master until the depression in the cylinder again comes under the pressure roller.

The feed tray 28 is constructed substantially as shown in the prior patent. It is provided with improved means whereby its position can be adjusted relatively to the carriage but such improved means form the subject of an application filed concurrently herewith and need not be described here.

The copy sheet is indicated at 54 and it is necessary that this should be pressed down on to the moistening pad 55 during the operation of the machine.

The means provided for doing this as described in the prior patent produced considerable friction operating against lateral movement of the carriage and according to the present invention I have substituted improved means whereby such friction is entirely eliminated.

For this purpose I provide two levers 9 pivoted at 56 to the bracket like portions of the arms 31 and these levers 9 are connected by a bar 57 adapted to be contacted at its upper side by screws 58 adjustably mounted in the lugs 50. These screws are provided with lock nuts 59 so that they can be set and then locked in position.

At its opposite end each lever is provided with a short stem 60 and these stems are connected by a bar or roller 61 adapted to engage the upper side of the copy sheet and press it down on to the moistener 55.

Angle section plates 62 are provided engaging the upper and end surfaces of the levers 9 and one side of each stem 60. The stems 60 have reduced portions which pass through the levers 9 and the angle 62 and are secured by nuts 63. A plate spring 64 engages one of these nuts 63 and this plate spring is mounted in a pin 65 which is fixed in the bracket-like portion of one of the arms 31. The pin 65 can be turned on its own axis and secured to adjust the pressure of the spring 64.

The levers 9 are thus spring loaded so that the bar or roller 61 is tending to move down on to the upper side of the copy sheet but is prevented from doing so by the screw 58.

During normal operation when the cylinder rotates it raises the pressure roller 39 and the associated stem 38 thus also raising the lug 50 and the screw 58 and permitting the levers 9 to rock and the bar or roller 61 to engage the upper side of the copy sheet.

As already explained there are a plurality of pressure rollers and sometimes all are used together and sometimes only one is used. When a pressure roller 39 is out of use it is raised by the spring 52 and consequently the pin 58 associated with that particular stem will be out of operation. Consequently the moistening bar or roller 61 will be put into operation by whichever of the pressure rollers is in operation and the moistening bar or roller 61 will be raised out of operation by the particular pressure roller and its associated parts which happens to be in operation.

The general form of the moistener is the same as that described in the prior specification but the moistener casing 66 is provided with an additional part 67 so that when the moistener is slid back out of operation the additional part 67 will sever the contact between the underside of the moistening pad and the wick 68 from which it receives moisture. Thus the flow of moistening fluid to the moistening pad will be stopped at all times when the moistening pad is out of operation.

In the present construction a mechanical coupling is established between the operating cam of each pressure roller and the associated moistening member the arrangement being such that the two work in sympathy i. e. they are brought into the operative position simultaneously and taken out of the operative position simultaneously by the operation of a single member this being the lever 47 of the cam.

Each moistening pad is provided with a wire stem 69 by which it may be withdrawn from the operative position and returned to the operative position and in accordance with the present invention this stem 69 is provided with a small bracket 70 to which is attached one end 71 of a Bowden cable the opposite end 72 of which is attached at 73 to one of the cams 46. Each of the cams is provided with a groove 74 to accommodate the Bowden cable.

The outer member 75 of the cable finds an abutment at one side 76 of the box in which the stems 38 slide and the opposite end of the outer member of the cable finds an abutment in a bar 77 extending between the plates 26.

In order to assist the movement of the moistening pad into the working position springs 78 are provided on the wires 69 these springs engaging against an adjustable stop plate 79 at one end and pushing against the end of the moistening pad at the opposite end.

The stop plate 79 is fixed on a pin 80 one end 81 of which forms an operating lever. The pin 80 is mounted for turning movement and endwise movement in the plates 26 and fixed on the pin is a collar 83 between which and the side of the adjacent plate 26 operates a spring 84 thus keeping the stop plate 79 in the position shown in Figure 5.

The stop plate 79 is prevented from turning in an anti-clockwise direction as seen in Figure 2 by means of a pin 82 on the inner side of one of the plates 26. If the rod 80 is pushed endwise to the left as seen in Figure 5 the stop plate 79 is moved bodily to the left and will clear the pin 82 so that it can then be turned by the lever 81 into a horizontal position thus allowing the moistening members to be completely withdrawn.

The lower edge of the stop plate is provided with a number of slots 85 which are of inverted L shape. When the stop plate is in the position shown in Figure 5 the wires 69 engage in the horizontal rims of the slots but when the plate 79 is pushed to the left as seen in Figure 5 it can readily be freed from the wires 69.

A large number of the slots 85 are provided because the moisteners may occupy any one of a number of positions and are laterally adjustable across the top of the tank.

As shown in Figure 4 each of the moisteners can slide between guide plates 86 and these guide plates can be adjusted by removing screws 87 and inserting them in fresh holes 88 in the top plate 89 which retains the guide plates 86 and the moisteners in position.

The key 90 for moving the carriage with a step by step motion laterally can be operated automatically to move the carriage one step at each revolution of the cylinder as in the prior patent this action being effected by a cam 91 on the end of the cylinder co-operating with a lever 92. This lever is somewhat modified as compared with that shown in the prior specification and the lever 92 is fixed to a rod 93 which can oscillate in the side plates of the machine. The lever is acted upon by a spring 94 and a stop 95 is provided to limit its motion under the influence of the spring 94. The lever 92 is provided with a portion 96 which engages the upper side of the lever 91 having the key 90.

What I claim then is:

1. In a duplicating machine, the combination with a cylinder having means for attaching a master sheet thereto, a box at a fixed distance from said cylinder, a plurality of stems slidably mounted in said box, and a pressure roller for cooperating with the cylinder mounted on each stem, of springs associated with said box tending to move each of said rollers away from the cylinder, and a cam in said box for each of said stems for displacing it towards the cylinder.

2. In a duplicating machine, the combination with a cylinder having means for attaching a master sheet thereto, a box at a fixed distance from said cylinder, a plurality of stems slidably mounted in said box, and a pressure roller for cooperating with the cylinder mounted on each stem, of springs associated with said box tending to move each of said rollers away from the cylinder, a cam in said box for each of said stems for displacing it towards the cylinder, and a single operating member for all of said cams.

3. In a duplicating machine, the combination with a cylinder having means for attaching a master sheet thereto, a box at a fixed distance from said cylinder, a plurality of stems slid-

ably mounted in said box, and a pressure roller for cooperating with the cylinder mounted on each stem, of springs associated with said box tending to move each of said rollers away from the cylinder, a cam in said box for each of said stems for displacing it towards the cylinder, a headed push pin engaging in the end of each stem, and a spring engaging between the head of each push pin and the adjacent end of the stem.

4. In a duplicating machine, a moistening means for sectionally moistening the copy sheets including a tank for copy sheet moistening liquid, a plurality of moistening members mounted on the top of the tank, and adjustable guide plates for the edges of the moistening members.

5. In a duplicating machine moistening means for sectionally moistening the copy sheets including a plurality of moistening members individually movable into and out of an operative position a stem attached to each of said moistening members, a stop plate extending at right angles to the direction of movement of said moistening members, and a spring on each of said stems acting between said stop plate and the moistener, said stop plate being releasable from said stems.

6. In a duplicating machine, moistening means for sectionally moistening the copy sheets including a tank for containing moistening fluid, said tank having an opening in its top, moistening members slideable over said opening, bracket like structures formed by upward extensions of the end plates of said tank, a stop consisting of a plate having a plurality of inverted L shaped slots in one edge, a stem attached to each of said moistening members, said moistener stems engaging in said slots, and a spring on each of said stems acting between said stop plate and the moistener, said stop plate being releasable from said stems and pivoted in said bracket like structures.

7. In a duplicating machine, the combination with a cylinder having means for attaching a master sheet thereto, a box at a fixed distance from said cylinder, a pair of stems slidably mounted in said box, a pressure roller for cooperating with the cylinder mounted on each stem, and springs associated with said box tending to move each of said rollers away from the cylinder, of a cam in said box for each of said stems for displacing it towards the cylinder, coupling means associated with said cams whereby they move simultaneously, said cams being disposed so that when one has moved its stem to the operative position, the other has permitted the other stem to move into the inoperative position.

8. In a duplicating machine, the combination

with a cylinder having means for attaching a master sheet thereto, said cylinder having a peripheral depression near to said master sheet attaching means, a box at a fixed distance from said cylinder, a plurality of stems slidably mounted in said box, a pressure roller for cooperating with the cylinder, mounted on each stem, springs associated with said box tending to move each of said rollers away from the cylinder, a cam in said box for each of said stems for displacing it towards the cylinder, levers rockable about a pivot axis parallel to and at a fixed distance from the cylinder axis, a pressing member for the copy sheets, carried by said levers, and an abutment on said stems for rocking said levers and raising the pressing member, when the cylinder has its peripheral depression under the pressure rollers.

9. A duplicating machine comprising a frame in which is mounted a cylinder having means for attaching a master sheet thereto, a guide carried by the frame, said guide being parallel to the cylinder axis, a carriage mounted on and movable along the guide, a box associated and moving with said carriage, a plurality of stems slidably mounted in said box, a pressure roller for cooperating with the cylinder mounted on each stem, springs associated with said box tending to move each of said rollers away from the cylinder, a cam in said box for each of said stems for displacing it towards the cylinder, a tray on said carriage for copy sheets, a plurality of moistening members on the carriage individually movable into and out of an operative position, motion transmitting, and means connecting each of said cams with a moistening member means in said box for each of said stems for displacing it towards the cylinder, said carriage being in two parts pivoted together, one part carrying the moistening means and the tray, and the other part including the box and the parts associated therewith.

10. In a duplicating machine, moistening means for sectionally moistening the copy sheets including a plurality of moistening members individually movable into and out of an operative position, each of said moistening members comprising a casing containing absorbent material said casing having an opening in its lower side, and means for feeding moistening liquid to said absorbent material through said opening, said casing having a portion which severs contact between the absorbent material and said moisture feeding means when said casing is moved into an inoperative position.

FRANK RONALD FORD.
